UNITED STATES PATENT OFFICE.

JOE IHNAT, OF NASHUA, MONTANA.

CATTLE-GUARD FOR RAILROAD-CROSSINGS.

1,391,384.

Specification of Letters Patent. Patented Sept. 20, 1921.

Application filed January 22, 1921. Serial No. 439,210.

To all whom it may concern:

Be it known that I, JOE IHNAT, a citizen of Czechoslovakia, residing at Nashua, in the county of Valley and State of Montana, have invented certain new and useful Improvements in Cattle-Guards for Railroad-Crossings, of which the following is a specification.

This invention relates to certain new and useful improvements in cattle guards for railroads and has particular reference to a cattle guard associated with a railroad crossing to prevent cattle in crossing a railroad from traveling along the tracks.

The primary object of the invention is to provide a cattle guard or screen at each side of a railroad crossing that normally assumes a horizontal position at a point below the track rails so as not to interfere with a railroad train in passing over the crossover.

A further object of the invention is to provide a cattle guard or screen adjacent the crossover of a railroad that is adapted to be operated and raised to a perpendicular position when cattle in traveling over the crossover attempt to travel in either direction over the tracks at opposite sides of the crossover.

A still further object of the invention is to provide a cattle guard in the form of a lattice screen work normally assuming a horizontal position beneath the level of the track rails and adapted to be elevated to a perpendicular position by a resiliently mounted cross bar adjacent the crossover when cattle attempt to leave the crossover and travel along the tracks.

With the above and other objects in view, the present invention consists in the novel form, combination and arrangement of parts hereinafter more fully described in connection with the accompanying drawings, and in which like reference characters designate corresponding parts throughout the several views,

In the drawings,

Figure 1 is a fragmentary top plan view of a portion of a railroad track showing the crossover and a cattle guard associated with each side thereof,

Fig. 2 is a side elevational view of the resilient trip device for operating the cattle guard,

Fig. 3 is a cross sectional view taken on line III-III of Fig. 2 showing the cattle guard in inoperative horizontal position and

elevated to its operative position as shown by dotted lines,

Fig. 4 is a fragmentary top plan view of a portion of the trip device and cattle guard, 60

Fig. 5 is a longitudinal sectional view taken on line V-V of Fig. 2 showing the connections between the sections of the trip device,

Fig. 6 is a fragmentary side elevational view of the trip device and a portion of the cattle guard elevated to its operative position, 65

Figs. 7 and 8 are fragmentary perspective views of the sections of the trip device, and 70

Fig. 9 is a fragmentary perspective view of a portion of the lever arm of the cattle guard detached from its pivotal connection with the trip device.

Referring more in detail to the accompanying drawings, and particularly to Fig. 1, there is illustrated a railroad crossing A over which the track rails 1 supported on ties 2 pass with fence guards B restricting the entrance to the crossing. The rails 1 adjacent the crossing A are supported on continuous cross ties 3. The cattle guards are positioned laterally of the inner supporting ties 3 and normally assume a horizontal position, the same being associated with trip devices adapted to move the cattle guards to a perpendicular position as shown in Figs. 3 and 4 upon operation of the trip devices to prevent the travel of the cattle along the track, 90

The trip device shown more clearly in Figs. 2 and 8 embodies a pair of telescoping members 4 and 5 of U-shape in cross section, the member 4 telescoping within the member 5 as shown in Figs. 2, 3, and 5. Coil springs 95 6 are interposed between the members 4 and 5 for normally holding the member 5 in the elevated position shown in Fig. 3, the springs being confined at their ends by the studs 7 formed on the adjacent faces of the 100 opposite walls of said members. To guide the members 4 and 5 in their telescoping movements, the member 4 is provided with cut away portions 8 in the side walls thereof between which the struck out angularly bent 105 flanges 9 of the side walls of the member 5 extend as shown in Fig. 5, thereby providing an interlocking connection between the telescoping members 4 and 5. A trip device is positioned at each side of the crossing be- 110

neath the track rails 1 outwardly of the central supporting ties 3 so that the cattle

guards associated with the trip devices may be independently operated at the direct point of travel of the cattle, in line with each track.

- 5 A transverse trip bar 9¹ is positioned outwardly of the trip devices at each side of the crossing A and is parallel therewith. The trip bar 9¹ is connected to the lower section 4 of the telescoping trip device, said 10 section being provided with struck out angularly bent lugs 10 shown more clearly in Figs. 3 and 8 that are secured by bolts 11 to the bar 9¹ while the upper face of the bar is provided with a metallic head strip 12 as shown in Fig. 3, the strips being secured to the bar by bolts or other fastening devices 13.

The cattle guard embodies a plurality of lever arms 14 carrying cross slats 15 with 20 the inner ends of the lever arms provided with bearings 16 for pivotal mounting in the side lugs 17 formed upon the upper edge of the section 5 of the trip device. The upper face of the lever arms 14 adjacent the 25 bearings 16 are provided with abutment lugs 18 for purposes presently to appear.

In the normal inoperative positions of the cattle guard sections, the same lie in a plane beneath the upper edge of the track rails 1 30 with the upper section 5 of the trip device moved to its limit of upward movement by the expansion springs 6 while the guard sections connected thereto rest upon the head rail 12 of the cross trip bar 9¹. The crossing A is unobstructed for transverse passage, but should cattle attempt to travel along either of the tracks, the section 5 of the trip device will be lowered against the tension of the springs 6 and carry therewith 35 the pivoted inner ends 16 of the guard lever arms 14, the guard arms engaging the cross bar 9¹ to be moved to a perpendicular position as indicated by dotted lines in Fig. 3, the abutment lugs 18 engaging the upper

edges of the section 5 to prevent an over- 45 throw of the cattle guard. The cattle guards are arranged in sections at each side of the track rails 1 and between the track rails while an independently operating trip device is associated with each track at opposite 50 sides of the crossing A. It will therefore be seen that cattle in attempting to travel along the track will operate the trip device to elevate the guard with the trip devices for each track at opposite sides of the cross- 55 ing being independently operable.

While there is herein shown and described what is believed to be the preferred embodiment of the invention, it is nevertheless to be understood that minor changes may be 60 made therein without departing from the spirit and scope of the invention as herein-after claimed.

What is claimed as new is:

A cattle guard for railroad crossings comprising a resilient trip device formed of telescoping sections of U-shape in cross section, interlocking connections between the telescoping sections including cut-out portions in the side walls of the lower stationary 70 section for receiving struck-out angularly bent flanges of the side walls of the upper sliding section, pairs of lugs carried by the upper edge of one section, a guard frame pivotally mounted in said lugs and means 75 disposed beneath said guard frame to move the same from a horizontal to a perpendicular position upon sliding movement of the telescoping sections, said means including a transverse bar fixed to one of the telescoping 80 sections.

In testimony whereof I affix my signature in presence of two witnesses.

JOE IHNAT.

Witnesses:

E. T. PETERSON,
J. C. JOHNSON.
